WIRE FABRIC

Clarence E. Pink, Cambridge, Md.

Application December 15, 1934, Serial No. 757,699

6 Claims. (Cl. 245—6)

The object of the invention is to provide a wire fabric particularly adapted for use as belting and designed to maintain its position on the driving pulleys or rolls as contradistinguished to the tendency to move laterally off of the rolls and pulleys in its movement; to provide a wire fabric belting in which the edging or selvage, while maintaining the elements of the fabric intact, permits free bending of the fabric, so that it may readily pass around the rolls or pulleys in close contact with the peripheral surface thereof; and generally to provide a wire fabric belting which is of simple form, susceptible of cheap manufacture, and of a character that will make it long lived under the most exacting conditions of service.

With this object in view, the invention consists in a construction and combination of parts of which a preferred embodiment is illustrated in the accompanying drawing, wherein:

Figure 1 is a top plan view of a section of the improved fabric.

Figure 2 is an edge elevational view.

Figure 3 is a sectional view taken on the plane indicated by the line 3—3 of Figure 1.

The improved fabric is constructed of a series of intercurrent right and left hand wire coils 10 and 11, which are coupled together by means of sinuous cross connectors 12 formed of wire strands. The coils 10 and 11 are open coils—that is, their convolutions are separated and, cross-sectionally, are of oval form, as clearly shown in Figures 2 and 3. The oval form of convolution makes for a belt or fabric of generally flat form, as distinguished from the form that would be presented were the convolutions truly circular.

The alternate bending of the cross connectors 12 provides series of spaced seats in which the convolutions of the connected coils 10 and 11 rest, the convolutions of the adjacent coils lying in successive oppositely disposed seats in the cross connectors, to maintain spacing of the coil convolutions.

The terminal convolutions of the coils are formed with eyes 13 engaging the terminal seats of the cross connectors 12.

Selvaging of the fabric is accomplished by means of links 14 and 15 arranged in intercurrent relation along the side edges of the belt or fabric, these links being made of wire strands of preferably the same gauge as that of which the coils and cross connectors are formed. The links are of generally S-shaped form by reason of terminal eyes provided by turning the extremi-

ties of the strand in opposite directions. The links 14 bridge each successive pair of cross connectors 12 and are preferably welded or otherwise secured to the extremities thereof. The links 15 bridge adjacent connectors of adjacent pairs but, having eyes formed in the same manner as those of the links 14, are preferably loosely mounted on the connectors and are retained in position thereon by the rigidly connected links 14. The links 14 are preferably mounted correspondingly on the several connectors, as are the links 15 on the connectors with which they engage, but the manner of mounting the links 15 is preferably the reverse of the manner of mounting the links 14, so that the selvage provided by the series of links follows a sinuous line of regular form as clearly shown in Figure 2.

Constructed as described, the belt or fabric comprises a series of alternate units each made up of a coil 10, a pair of cross connectors 12 and 20 a pair of oppositely disposed links 14 which constitute substantially an assemblage of rigidly connected elements. These separate units are interconnected by the coils 11 and their associated links 15. But this arrangement of parts provides for free relative swinging movement of interconnected units, so that the belt or fabric may readily conform itself to the periphery of the engaged pulley or roll and the edging provided by the links 14 and 15, in conjunction with the seats formed in the cross connectors, is means to prevent lateral displacement of the units while taking up but a minimum space at the side edges of the belt, so that the belt need be no wider, practically, than the width of the desired working area thereof.

The invention having been described, what is claimed as new and useful is:

1. A wire fabric comprising a series of intercurrent right and left hand wire coils having the convolutions thereof uniformly spaced, sinuous wire cross connectors threaded through the convolutions of adjacent coils, and a selvage comprising links bridging the extremities of successive cross connectors, certain of the links being loosely mounted on the cross connectors and the remaining links being rigidly secured to said cross connectors and maintaining the loosely mounted links in place.

2. A wire fabric comprising a series of transversely arranged wire coils, cross connectors threaded alternately through the succeeding convolutions of adjacent coils, and a selvage for the fabric comprising links bridging the extremities of adjacent connectors and being in part rigidly

connected with said connectors and in part loosely connected with the same.

3. A wire fabric comprising a series of transversely arranged wire coils, cross connectors threaded alternately through the succeeding convolutions of adjacent coils, and a selvage for the fabric comprising links bridging the extremities of successive pairs of cross connectors to which they are rigidly connected, and additional links arranged in intercurrent relation with the first said links and bridging but being loosely connected with the adjacent connectors of adjacent pairs.
4. A wire fabric comprising a series of transversely arranged wire coils, cross connectors threaded alternately through the succeeding convolutions of adjacent coils, and a selvage comprising a series of links formed of wire strands terminally bent to provide terminal eyes, said cross connectors having their extremities passed through the eyes of the links and the alternate links being rigidly secured to the connectors while

the intervening links are loosely engaged therewith.

5. A wire fabric comprising a series of transversely arranged wire coils, cross connectors threaded alternately through the succeeding convolutions of adjacent coils, and unconnected links bridging the cross connectors in successive pairs and consisting of wire strands terminally wound around and rigidly secured to the extremities of the cross connectors.

6. A wire fabric comprising a series of transversely arranged wire coils, cross connectors threaded alternately through the succeeding convolutions of adjacent coils, and unconnected links bridging the cross connectors in successive pairs and consisting of wire strands whose extremities are oppositely coiled to provide terminal eyes receiving the extremities of the cross connectors to which latter they are rigidly secured.
